(57) **CLAIM**

The ornamental design for a modular air handler for pallet racking system, as shown and described.

DESCRIPTION

FIG. 1 is a top-front perspective view of a modular air handler illustrating my new design, shown with an upper portion of the frame extended relative to the lower portion; FIG. 2 is a bottom-rear perspective view thereof;

FIG. 3 is front elevation view thereof;

FIG. 4 is rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top-front perspective view thereof, shown with the upper portion of the frame contracted relative to the lower portion; and,

FIG. 10 is a bottom-rear perspective view thereof.

The broken lines depict portions of the modular air handler for pallet racking system that form no part of the claimed design.
